United States Patent Office

Des. 219,012

Patented Oct. 27, 1970

219,012

POWERED MOBILE HOME

Arthur F. Tarabusi, Orchard Lake, Mich., Glen L. Broome, La Moille, and George E. Steinmetz and Richard G. Vickery, Winona, Minn., assignors to Krager Kustom Koach, Inc., Winona, Minn., a corporation of Minnesota

Filed Dec. 24, 1969, Ser. No. 20,630

Term of patent 14 years

Int. Cl. D12—08

U.S. Cl. D14—3

FIG. 1 is a view in side elevation of a powered mobile home showing our new design;

FIG. 2 is a view in top plan thereof, on a slightly reduced scale;

FIG. 3 is a view in side elevation thereof, showing the side opposite that shown in FIG. 1;

FIG. 4 is a view in rear elevation thereof, on a slightly reduced scale; and

FIG. 5 is a view in front elevation thereof, on a slightly reduced scale.

The bottom not shown is substantially devoid of ornamentation.

We claim:

The ornamental design for a powered mobile home, substantially as shown and described.
